UNITED STATES PATENT OFFICE

2,191,768

VENTILATOR

Harold L. Moose, San Francisco, Calif.

Application December 14, 1938, Serial No. 245,794

3 Claims. (Cl. 98—99)

My invention relates to ventilators and more particularly to those which are adapted to be positioned in a window in a simple and efficient manner.

- 5 An object of the invention is to provide a simple, compact and inexpensive type of ventilator which, when in place in a window, will supply ventilation and exclude fog, wind, rain, insects and dust from the room being ventilated.
- 10 Another object of my invention is to provide a ventilator which may be easily and firmly inserted into and removed from the grooves of a window frame and which may be positioned for use by closing one or the other of the window 15 sashes upon the top of the ventilator.

Other objects and advantages of the invention will appear from the specific description following:

- Reference is had to the accompanying drawing 20 forming part of this specification, in which similar characters represent corresponding parts in all the views. In said drawing, I have shown one form of the construction of my invention, but it is to be understood that I do not limit 25 myself to such form, since the invention as expressed in the claims may be embodied in other forms.

In the drawing—

- Figure 1 shows an elevation from the interior 30 showing a ventilator according to my invention in place in a window frame and attached to a window;

- Figure 2 shows a vertical sectional view of a 35 ventilator as shown in Figure 1 along axis A—A; and

- Figure 3 shows a vertical cross-section of a portion of the frame member taken along axis B—B of Figure 2, showing the means for contracting and expanding said frame member.

- 40 Figure 4 shows a sectional view of a portion of a form of my invention showing the ventilator supported in the outer channel of a window frame with an extension of the canopy attached to the lower window mounted in the inner channel of said frame.

- 45 In one embodiment of my invention I provide a rectangular frame 1 which may be of wood or any other desirable material, such as metal. This frame is constructed by forming two horizontal members with two end members, the horizontal members being separated intermediate the ends thereof to make the frame into two sections shown as 1a and 1b. At the points of separation means are provided to permit expansion 50 and contraction of the frame for insertion into

and removal from the grooves or window guides of a window frame. This means is in the form of extensions on one of said sections which are slidably mounted in corresponding openings in the other of the frame sections. In the drawing, as shown in Figure 3 in detail, these extensions are shown as a pair of dowel pins 8 affixed to each frame member 1a and slidably mounted in openings 9, in the opposite frame members. Springs 14 are positioned in each opening to normally maintain the frame in expanded position, while permitting contraction of the frame by pressure on the ends. The length of the dowels and the openings are regulated so as to allow sufficient contraction to permit insertion 15 of the frame into the window grooves. After insertion of the frame, the springs will cause expansions and the frame sections may then be clamped in expanded position by clamp 17 in which slot 11 is engaged by a clamping nut 10 of the wing type. A handle 12 is provided to permit easier contraction of the frame for insertion or removal after clamps 17 have been disengaged.

20 As shown in Figure 2, upright frame 1 is provided with a folding U-shaped frame 13, the ends of which are hinged to frame 1 as shown at 16. A flexible canopy or awning 3 is mounted on the two frames in a manner to permit folding and to give suitable protection in the window frame. The canopy 3 is fastened at the top of frame 1 and at the edge of frame 13 as shown, and also has sides shown at 18 in Figure 1, so that when the ventilator is in place, all but the underside of frame 13 and the rear side of frame 1 are 25 enclosed.

30 As shown in Figures 1 and 2, a screen 7 may be mounted on frame 13, this screen being flexible or collapsible to allow expansion or contraction of frame 1. This flexibility may be provided by making the screen loose or providing a tuck therein, or by using a conventional type of collapsible screen. As a matter of fact, a screen mounted in the usual manner is sufficiently 35 flexible to allow contraction of the frame 1 sufficiently to allow insertion thereof in the window frame.

40 Canopy 3 extends beyond the top of frame 1 to which it is affixed, this extension forming an apron 4 passing between the top of the frame and the bottom sash of the window. This apron has loops 5 attached to the edge thereof which are fastened to window lifts 6, or in case the window has no lifts, to hooks or the like, attached to the bottom of the window. This apron 45 50 55

passing under the window will prevent the penetration of rain or wind, etc., through the crack between window and frame, and will also give the awning or canopy additional support.

- 5 In the installation of my ventilator, a suitable size is selected, the window opened, the clamps 11 are unfastened, handle 12 is grasped with one hand, and the opposite side of the frame with the other, and the dowels 8 are shoved into 10 grooves 9 compressing openings 14. The frame, while compressed, is inserted into the grooves of the window frame resting on the bottom 15 of said frame, and the handle 12 is released, expanding the springs 14 and securing the frame in the 15 grooves. Slots 11 are then slipped over the bolts holding wing nuts 10 which are then tightened making frame 1 rigid. The window 2 is then closed on top of frame 1 with apron 4 on the inside. Loops 5 are then attached to the window 20 lifts 6, and if necessary the window may be raised slightly to make the apron taut.

If the ventilator is to be placed in the top portion of the window frame, the upper sash of the window may be lowered and the same procedure 25 followed. In this case, the use of the apron 4 may be dispensed with, or the loops thereof may be attached to the upper part of the frame.

In the form of my invention described in Figure 4, the installation is similar to that described 30 with respect to the modification shown in Figure 2, the frame and canopy being constructed in a similar manner. In this embodiment it is found desirable to mount the frame 1 in the lower portion of the outer channel 19 in a window frame 35 constructed with a pair of vertical channels in which the upper and lower windows ride. The lower window 2, which rides in inner channel 20 is then raised so that its lower portion is opposite the top of frame 1, and the apron or canopy 40 extension 4 is passed underneath the bottom portion of the sash of window 2 and the loops 5 or other attachment members are attached to the lifts 6 on the window sash, or to other fastening means on the window frame as described with 45 reference to the modification shown in Figure 2. The advantage of this form of my invention resides in the fact that the ventilator may remain permanently in the window frame since, when it is desired to close the lower window, the loops 50 on the apron may be detached from the fastening means on the window frame. When this is done, the window may be lowered in its inner channel, and the ventilator remains in the outer channel ready for use.

55 When it is desired to use the ventilator of my invention in window frames which do not have channels of the type referred to, or where it is not desired to mount the said ventilator in the channel, my ventilator may be fastened in the 60 window frame by other means, such as by means

of hooks or clamps, the frame of the ventilator being mounted on the exterior of the window frame. The lower window is then opened to the appropriate height and the canopy extension or apron may be passed under the window and attached as described above. When the extension is detached, the ventilator will remain in place for use, and the window may be raised or lowered in the usual manner.

Although but one specific embodiment of my invention has been shown and described, it will be understood that numerous other details of the construction shown may be altered or omitted without departing from the spirit of this invention as defined by the following claims.

I claim:

1. A ventilator comprising an upright frame, a second frame secured to and extending outwardly from said upright frame, an awning canopy extending from the top of said upright frame downwardly to the front portion of said second frame, an extension on said canopy equal in width thereto and having a continuous surface passing beyond the top of said upright frame and adapted to pass beneath the bottom of a window sash positioned above said upright frame, and means for attaching said extension on the interior above the bottom of the window sash.

2. In combination, a window frame, an upright rectangular frame mounted therein, a second frame secured to said upright frame and adapted to extend outwardly therefrom, an awning canopy supported on said frames extending to the exterior from the top of said upright frame, an extension on said canopy passing beyond the top of the upright frame and beneath the bottom sash of a window in said frame, said extension defining a continuous surface between the bottom of said window sash and the top of said upright frame, and means for attaching said extension above the bottom of the sash on the interior of the window.

3. A ventilator of the class described comprising a rectangular upright frame having horizontal members and end members, each of said horizontal members comprising two separate portions, one of said portions on each of said members having an extension thereon engaging a corresponding opening in the other portion to permit expansion and contraction of said upright frame, a second frame secured to said upright frame and adapted to extend outwardly therefrom, a canopy attached to the top of said upright frame and to said second frame, and an extension on said canopy defining a continuous surface over the width of the canopy and extending beyond the top of said upright frame for attachment to a window on the interior thereof above the bottom of the window sash.

HAROLD L. MOOSE.
